UNITED STATES PATENT OFFICE.

GEORGE P. JACKSON, OF FLUSHING, NEW YORK, ASSIGNOR TO COMBUSTION ENGINEERING CORPORATION, OF NEW YORK, N. Y., A CORPORATION OF NEW YORK.

TILE-ANCHORING DEVICE.

Original application filed April 21, 1923, Serial No. 633,609. Divided and this application filed April 14, 1925. Serial No. 22,945.

This invention relates to tile anchoring devices, such for instance, as are used for the support of tile or brick furnace walls or linings, and this application is a division of my co-pending application, No. 633,609, filed April 21, 1923, which illustrates a furnace wall where such anchoring devices are used.

It is now customary in the art of burning pulverized fuel to make the furnace walls hollow and to pass air for combustion through these walls for the purpose of preheating it in order that greater efficiency of combustion may be obtained. As a result, the furnace temperatures attained are greater and the walls are subjected to a more intense heat. The air circulating within them, however, is continually absorbing such heat. It consequently serves a two-fold purpose, namely, the increasing of combustion efficiency, and the cooling of the furnace walls with its consequent saving of the brickwork.

On account of variations in the rate of firing and consequent differences in the length of the downward travel of the fuel-and-flame stream, which will not always extend down the full length of the furnace wall, it is desirable to divide the space within the wall into horizontal compartments or ducts so that air may be circulated through one or any number of them. For this purpose horizontal layers of holding tile are provided in the inner wall which act not only as partitions to form the ducts but are used to support the inner wall laterally from the outer.

Since the inner wall is subjected to greater heat than the outer, and is itself subject to the action of the flame on its inner face and the action of the cooling air on its outer face, it must therefore expand more than the outer wall, as well as have some tendency to buckle or collapse.

My invention is primarily the provision of an anchoring device to support the holding tile from the outer wall which at the same time will allow for sufficient relative freedom of motion between the walls to prevent the shearing off of the holding tile. It also provides for freedom of expansion and contraction of the bricks and for vertical and longitudinal movements in the wall due to such expansion and contraction. A further object of the invention is to make the renewal and replacement of the refractory bricks a simple and easy matter.

The foregoing advantages, and others which may occur to those skilled in the art, I obtain by means of the construction illustrated in the accompanying drawings, wherein:

Fig. 1 is a vertical section of part of a hollow-wall pulverized fuel furnace showing an application of my invention;

Fig. 2 is a view in perspective of one of my anchoring members; and

Fig. 3 is a perspective view of an alternative form of the anchor.

Referring first to Fig. 1, I have illustrated the forward upper quarter of a pulverized fuel combustion chamber 7 with its front wall 8, roof 9, fuel burner nozzles 10 and water tubes 11. The wall 8, at the upper part of the furnace, as shown, is of hollow construction, the outer portion of the wall being built up of vertical steel beams or buck-stays 12, attached to which on the inner side are horizontal I or H beams 13. Built up on the beams 13 and supported by them is a wall of bricks 14, or other suitable material, which may have on its outer side a thermo-insulative covering 15, for instance a layer of asbestos. The inner portion of the wall is a refractory lining built up of alternate horizontal courses of holding tile and bricks 16 and 17, supported vertically, independent of the outer wall, on the part 18 of the wall 8. At the top of this refractory lining is a filler block 19, or other suitable closure between the outer bricks 14 and the roof 9, this arrangement constituting a slip-joint to allow for movement of the refractory lining due to expansion and contraction. The passages 20 which may extend either part way or entirely around the furnace are the conduits for the air, which, after being heated by its passing through said conduits, is ordinarily admitted into the combustion chamber 21 through the ports 21 arranged, at suitable intervals, to mingle the said air with the downwardly directed fuel-and-flame stream from the burner nozzles 10.

My invention, designed to support the lining laterally, is the gripping member 23, which, as clearly shown in the enlarged view of Fig. 2, is of substantially T-head cross section, having a head 24, a web 25, and hook-like fingers 26, 27. It may also have raised surfaces or abutments 28, on the edge of the web-like portion 25, to bear against the I beam 13.

My anchoring device, applied as shown,

with the fingers 26, 27, gripping the flanges of the I beam, and the head 24 and web 25 fitted into a substantially T-shaped vertical slot in the refractory brick 16 or into corresponding grooves in the edges of two adjacent bricks, effectually holds the refractory wall from lateral displacement but at the same time permits the necessary vertical movement of said wall without danger of breaking or cracking the brick 16. The members 23 are preferably spaced at suitable distances horizontally to allow the fingers 26, 27 to fit between adjacent blocks 14, and they may be welded in position on the I beams 13 or left free in cases where some horizontal sliding of the gripper along the I beam is desirable.

A certain amount of horizontal movement in the wall, however, is taken care of by a slight rocking movement of the bricks around the heads 24 of the grippers, and for this purpose I make the head 24 with a substantially curved surface, or in other words, with a somewhat oval cross-section.

The alternative form of my invention, as shown in Fig. 3, is for use in furnaces where the brick-supporting I beams of the outer wall run vertically instead of horizontally, and its application will, I believe, be clear without further explanation. It is necessary in this instance, of course, that the web 25 be very narrow since it is crosswise of the head and must fit a narrow groove or slot in the brick.

The ease with which the refractory lining of a furnace can be built up, taken down, or repaired is quite obvious, the locking bricks 16 being merely slid up or down on the T heads 24 of the grippers.

I claim:

- 40 1. A brick-anchoring member comprising a brick-engaging head curved convexly across its outer face, support engaging means constructed to prevent displacement of the member inwardly or outwardly from the support and a web connection between the head and the support-engaging means.
- 45 2. A brick-anchoring member of substan-

tial T-section, the head of the T being curved for interlocking but rocking engagement in a re-entrant recess in the member to be 50 anchored, and the leg of the T having means for gripping a support.

3. A T-shaped anchoring member for tiles, said member having a head and a web with support engaging means on the web and with 55 the head curved across its outer face, said support engaging means comprising two inwardly extending hooks.

4. An anchoring member of substantially T cross-section, the head of the T being 60 curved across its outer face and adapted to interlock with a recess in the member to be anchored, and the leg of the T having fingers adapted to engage the flanges of a supporting girder.

5. A brick-anchoring member having 65 means to engage a support on one side as against lateral movement in either direction; and means to interlock with a brick on the other side, said means being formed to provide freedom for sliding motion of the brick in one plane and rocking motion in another plane, relative to the anchoring member.

6. A wall structure comprising, in combination, a wall with re-enforcing girders 70 therein, another wall adjacent thereto, said second wall having at intervals bricks with re-entrant recesses, and anchoring members each adapted to engage a girder of the first wall and having means to interlock with a 75 recessed brick of the second wall with freedom for vertical sliding motion and horizontal rocking motion between said bricks and anchoring members.

7. A T-shaped anchoring member for tiles, 80 said member having a head with a curved surface, and a web, with support-engaging means on the web adapted to prevent lateral displacement of the member in either direction.

In testimony whereof, I have hereunto signed my name.

GEORGE P. JACKSON.
